AUXILIARY CLOTH WINDING MEANS FOR LOOMS

Milton Ray Harden, Stonewall, Miss., assignor to
Erwin Mills, Inc., Durham, N. C., a corporation
of North Carolina

Application February 12, 1951, Serial No. 210,504

2 Claims. (Cl. 139—308)

1

This invention relates to apparatus for handling cloth which is being woven in a loom and, instead of winding the cloth onto a take-up roll which is resiliently pressed into engagement with the sand roll of the loom, there is substituted for the pressure roll which engages the sand roll, a suitable pressure roller which engages the sand roll, and the sand roll, being driven, feeds the cloth between the sand roll and the pressure roll downwardly through a slot in the floor on which the loom rests and onto suitable take-up mechanism disposed on the floor below the floor on which the loom rests. This permits the running of an entire warp on the loom yarn beam into a roll of cloth before doffing. It also removes from the aisle between the looms the projecting cloth beam as it builds up to a size where it must be doffed to prevent restricting the passageway or aisle between the looms to too great an extent.

It is therefore an object of this invention to provide a loom with a pressure roller resiliently held in engagement with the sand roll of the loom for the passage of cloth woven by the loom between the sand roll and the pressure roll and extending the cloth downwardly through an elongated slot in the floor to suitable take-up apparatus disposed on a floor below where the cloth can be wound into much larger packages than has heretofore been possible in conventional looms wherein the cloth is wound onto a take-up roll resiliently pressed into engagement with the sand roll.

Some of the objects of the invention having been stated, other objects will appear as the description proceeds when taken in connection with the accompanying drawings in which—

Figure 1 is a vertical sectional view through two floors of a building and showing the apparatus installed on the floors;

Figure 2 is an enlarged elevation with parts broken away looking from the left-hand side of Figure 1;

Figure 3 is a side elevation of the cloth take-up apparatus shown in the lower portion of Figure 1 and looking at the opposite side thereof from that shown in Figure 1 with parts in a different position;

Figure 4 is a top plan view looking down on Figure 3;

Figure 5 is an enlarged vertical sectional view similar to the upper left-hand portion of Figure 1 but showing the parts in more detail;

Figure 6 is an elevation looking from the left-hand side of Figure 5;

Figure 7 is a fragmentary vertical sectional

view taken substantially along the line 7—7 in Figure 2.

Referring more specifically to the drawings, the numeral 10 indicates a conventional loom having a warp beam 11, swords 12, lay 13, suitable harnesses 14, warp 15 and a sand roll 16. This sand roll is driven in any suitable manner such as by a train of gearing 17, 18, 19 and 20 and has extending therefrom a shaft 21. The loom is also equipped with a suitable mechanism such as is shown in the patent to William H. Bahan, Number 2,519,424 of August 22, 1950 and comprising a torsionally biased shaft 25 having a pinion 26 on each end thereof which engages a rack on the lower end of members 27 whose upper ends have suitable notches therein for reception of a cloth take-up roll as set forth in said patent.

However, in the present instance instead of a cloth take-up roll there is provided a roller 30, preferably having a rubber covering 31 thereon, and cloth 15a, resulting from weaving of a suitable filling with the warp threads 15, passes over the sand roll 16 and between the sand roll 16 and the pressure roll 30 and then extends downwardly and rearwardly at an angle, over a rod 16a and rearwardly of the shaft 25 and then through a suitable slot 32 in the floor on which the loom rests. It is thus seen that the cloth is not wound onto a cloth take-up roll supported by the members 27 and thus the size of the cloth roll is not limited to the distance downwardly which the member 27 can move.

The cloth roll take-up mechanism disposed below the floor on which the loom rests comprises 35 a frame having vertical uprights 40 and 41 and horizontal portions 42 and 43 and diagonal legs 44 and 45, all of which are integral with each other and are also integral with a plate 46 disposed on the floor on which the cloth take-up apparatus rests. The vertical members 40 and 41 are secured to each other by means of a suitable shaft 47 passing through a tube 48.

On top of the horizontal members 42 and 43 there are provided bearing blocks 50 and 51 in 45 which stub shafts 52 and 53 extending from a roller 54 are mounted. On stub shaft 53 is fixed a sprocket wheel 55 having a sprocket chain 56 mounted thereon. Said sprocket chain extends upwardly through a slot 57 in the floor on which 50 the loom rests and is mounted on a sprocket wheel 58 secured on the end of the shaft 21 extending from the sand roll 16.

In this manner, the roll 54 is driven by the sand roll and in timed relation thereto. Pivoted 55 on the angle members 44 and 45, as at 60 and 61,

are spaced support bars 62 and 63 which are adapted to support a lap pin 64 on which a suitable tube 65 is placed and, in the beginning of a winding operation, this tube 65 will be in frictional contact with the drive roll 54 and the cloth 15a will be wound therearound with the parts in the position shown in Figure 1.

In order to manipulate the support bars 62 and 63, there is pivotally secured to these bars, as at 70 and 71, a second pair of links 72 and 73 which are, in turn, pivoted, as at 74 and 75, to a first pair of links 76 and 77 whose lower ends are fixedly secured on a shaft 78 having an upturned lever 79 integral therewith. The shaft 78 is oscillatably mounted in the diagonal members 44 and 45.

In order to hold the parts of the cloth take-up apparatus in the position shown in Figure 1, there is provided a plate 82 which is welded to the diagonal angle bar 45 having a notch 83 in its upper end. The lever arm 79 has a projection 84 thereon on which is pivoted, as at 85, a dog or latch 86. Now, when the parts are elevated to the position shown in the lower portion of Figure 1, the dog 86 will ride through a slot 45a in the angle bar 45 and over a sloping portion 87 on the plate 82 and drop into the notch 83 to hold or latch the parts in elevated position so that, as the cloth is built up on the cloth roll, the lap pin 64 along with the cloth roll will ride upwardly on the spaced support bars 62 and 63 until the entire contents of the warp beam has been woven or until it is decided to sever the cloth and remove the cloth roll from off the angle bars 62 and 63.

When it is desired to do this, the operator seizes the lever 79 and raises the latch 86 which will permit the parts to move, by gravity or by being moved by the crank arm 79, to the position shown in Figure 3 where the cloth roll can be doffed.

It is thus seen that there has been provided simple and inexpensive apparatus for receiving the cloth from a loom at a point remote from the loom without the necessity of the build up of the cloth roll in association with the sand roll narrowing the aisle spaces between the looms and limiting the size of cloth roll which can be woven before doffing.

In the drawings and specification, there has been set forth a preferred embodiment of the invention, and although specific terms are employed, they are used in a generic and descriptive sense only and not for purposes of limitation, the scope of the invention being defined in the claims.

I claim:

1. In a loom having a driven sand roll, the combination of a cloth winding apparatus having a fixed frame, a roll in the fixed frame driven by the sand roll, a pair of spaced support bars,

said support bars being adapted to support a lap pin, means pivoting one of the ends of the support bars to the fixed frame at points adjacent to but at a lower level than the driven roll, whereby when the free ends of the support bars are moved upwardly the lap pin will move by gravity into contact with the driven roll, an oscillatable shaft mounted in a lower portion of the fixed frame and having a lever fixed thereto, a first pair of links having one of their ends secured to the oscillatable shaft, a second pair of links having their upper ends pivotally secured to the support bars, means pivotally securing the lower ends of the second pair of links to the upper ends of the first pair of links and means for latching the lever against movement when the first and second pairs of links are in alignment with each other.

2. A cloth winding apparatus having a fixed frame, a driven roll in the fixed frame, a pair of spaced support bars, said support bars being adapted to support a lap pin, means pivoting one of the ends of the spaced support bars to the fixed frame at points adjacent to but at a lower level than the driven roll whereby when the free ends of the support bars are moved upwardly, the lap pin will move by gravity into contact with the driven roll, an oscillatable shaft mounted in a lower portion of the fixed frame and having a lever fixed thereto, a first pair of links having one of their ends secured to the oscillatable shaft, a second pair of links having their upper ends pivotally secured to the support bars, means pivotally securing the lower ends of the second pair of links to the upper ends of the first pair of links and means for latching the lever against movement when the first and second pairs of links are in alignment with each other.

MILTON RAY HARDEN.
